DOUBLE WINDOW CONSTRUCTION

Roy T. Axe, Syracuse, N. Y., assignor to The O. M. Edwards Company, Inc., Syracuse, N. Y., a corporation of New York

Application January 26, 1939, Serial No. 252,949

2 Claims. (Cl. 189—64)

This invention relates to window structures for railway cars, buses, and other enclosures, and has for its object a mounting for double glass panels including a resilient spacer between the glass panels with means tending to spread the spacer laterally against the glass panels and keep the same snugly engaged therewith, and with the remainder of the mounting on the outer sides of the glass panels, under varying outside air pressure conditions, and thereby keeping the space between the glass panels hermetically sealed to prevent seepage of outside air into the space and the air from said space to the outside. When there is a low barometer or the outside air pressure is low, the glass panels tend to separate and the air seep from between the glass panels to the outside thereof. When there is a high barometer or the outside air pressure is high, the glass panels are pressed toward each other and the air tends to seep from outside the glass panels to the space between them.

More specifically, the invention has for its object a mounting of resilient material which tends to follow up the movements of the glass panels occurring during low and high outside pressures, including a spacer between the glass panels, which also has the follow-up movement, or a spacer including wedging or spreader means, which means tends to spread the spacer laterally and keep it snugly engaged under all conditions with the margins of the glass panels.

It further has for its object a mounting for spaced apart glass panels, which mounting is of compressible resilient material, as rubber, or includes glazing strip and spacer portions of such material, together with means, as a shield, for protecting the exposed surfaces of the glazing strip and the spacer portions against deterioration from the sun and weather. It will be understood that the moisture taken into the pores of the rubber in cold weather freezes and tends to destroy the rubber, and also the sun in warm weather dries out the rubber.

The invention consists in the novel features and in the combinations and constructions hereinafter set forth and claimed.

In describing this invention, reference is had to the accompanying drawing in which like characters designate corresponding parts in all the views.

Figures 1, 2 and 3 are fragmentary isometric sectional views of sash glass mountings embodying different forms of the invention.

Figure 4 is a fragmentary isometric view of a

modified form of spacer of that shown in Figure 1.

Figure 5 is a fragmentary isometric view of the wedging means for spreading the spacer shown in Figure 3.

Figure 6 is an isometric view of the shield or sheath for the outer glazing strip.

Figure 7 is a sectional view of the spacer illustrating another form of protecting sheath for the spacer.

1 designates the sash which may be of any suitable form, size and construction. 2 and 3 designate, respectively the glass panels. The mounting by which these panels are carried in the 15 sash includes glazing strips 5, 6 coacting with the outer faces of the glass panels 2, 3 and a spacer 7 located between the glass panels, the glazing strips and the spacer being of resilient compressible material, as rubber, capable of having a 20 give-and-take and a follow-up movement.

The sash is formed with channels at 8 and 9 at its inner and outer sides for receiving the base flanges 10 and 11 of the glazing strips.

The spacer 7, in addition to the portion extending 25 between the glass panels 2, 3, includes a base flange 12 extending into a groove 13 in the sash and also laterally extending portions 14 which extend across the edges of the glass panels. The spacer is also formed with a lengthwise channel 30 for receiving a spreading or wedging means.

In the form shown in Figure 1, the channel 15 opens through a contracted entrance 15a through the inner face of the spacer and the wedging means is a cord 16 circular in cross-section, which is pressed into the channel 15 through the contracted entrance, and the spreader or cord 16 fits or interlocks in the channel to the inward of the contracted entrance. The cord is preferably of a resilient material, as rubber.

In the form shown in Figure 2, the construction is substantially the same as that shown in Figure 1, with the exception of the spacer. In this construction, the spreading means is provided on the sash 1 and the spacer 17 is provided with a channel 18 corresponding to the channel 15 but opening through the outer edge of the mounting means, and the portion of the spacer 17 between the glass panels is formed hollow with the side portions thereof bowing or bulging outwardly. The wedging or spreading means is a rib 19 on the sash extending into the channel and tending to spread the spacer 17.

In Figure 4, another form of spacer, analogous to that shown in Figure 1, is shown including the portion 20 of the spacer, which portion ex-

tends between the glass panels and is provided with a V-shaped groove 21 opening through the inner edge of the spacer in which is pressed a wedge or spreader of resilient material.

In Figure 3, a different form of sash is shown for the glass panels including a body portion 23 seated in a right angular channel in the sash 24 and abutting at one side against the fixed side 25 of the channel, and a glazing strip 26 on the other side of the sash. The body of the mounting is formed to receive the margins of the glass panels with the spacer 27 between them, and this spacer is formed with a lengthwise channel opening through the inner edge of the spacer. The spacer is spread apart by a resilient metal wedge 28, V-shaped in cross-section, and tensioned to press the arms of the V formation outwardly.

The wedge or spreader 28 is insertable in the channel of the spacer and is provided with outwardly flaring lips which cover the exposed edge of the spacer with the exception of narrow lips at 30 adjacent the glass panels. The spreader 28 thus acts also as a shield to protect the spacer from deterioration. Also, the glazing strip 26 and the glazing strips 5, 6 (Figure 1) are covered by a sheath or shield 31, usually of metal, this having a base portion 32 angular in cross-section extending into the groove of the frame in which the glazing strip is seated, and an outer portion 33 conforming to the outer contour of the bead or head of the glazing strip. Preferably, the bead or head is formed with a lip 34 lapping over the edge of the shield or sheath to cover the same.

In Figure 7, the spacer is shown as provided with a sheath 35 in the form of a channel-shaped cap embracing a projecting margin of the spacer and of less width than the adjacent portion of the spacer, which presses against the glass panels. The sheath or cap 35 thus protects the exposed edge of the spacer against deterioration but does not modify the compressibility or resiliency of the spacer.

In any form of the invention, the spacer portion of the mounting for the glass panels 2, 3 may, during installation, be placed under sufficient tension, so that it may spread or expand and contract to compensate for variations occurring during the fluctuations in the outside air pressure. The remainder of the mounting, including the glazing strips, also give and take under the same conditions, so that the air space between the glass panels remain under the fluctuations in the outside air pressure, hermetically sealed.

What I claim is:

1. A double window construction comprising a sash having resilient means for mounting a pair of spaced apart glass panels including a resilient spacer carried by and interlocked with the sash and extending between the margins of the glass panels, the spacer being formed with a lengthwise channel opening through its inner edge, and wedging means located in the channel and spreading the side portions of the spacer to press against the margins of the glass panels, said wedging means being a strip of metal V-shaped in cross-section tensioned to spread the arms of the V formation laterally.
2. A double window construction comprising a sash having resilient means for mounting a pair of spaced apart glass panels including a resilient spacer extending between the margins of the glass panels, the spacer being formed with a lengthwise channel opening through its inner edge, and resilient wedge means of spring metal fitting the channel, said wedge means having laterally extending lips covering the outer edge of the spacer to protect the same, the edges of the lips being spaced from the glass panels, whereby they are out of contact with the glass panels, thereby permitting compression of the spacer between the glass panels.

ROY T. AXE.
